SUPERHEATER

Howard J. Kerr, Westfield, N. J., assignor to The
Babcock & Wilcox Company, Newark, N. J.,
a corporation of New Jersey

Application July 18, 1934, Serial No. 735,780

21 Claims. (Cl. 122—479)

This invention relates to fluid heat exchange apparatus and is more particularly concerned with improvements in the superheating of fluids used under high pressure.

5 An object of the invention is to provide improved apparatus for controlling and maintaining a constant superheat. A more specific object is to accomplish this control in such a manner that the superheating operation is further improved by the reduction of solids which may be contained in the steam entering the superheater, such reduction taking place before the steam enters that section of the superheater which is subjected to furnace gases of high temperature.

10 15 The operative life of the tubes of this section is thereby materially increased.

20 A further object of the invention is to accomplish superheat control by the use of a contact desuperheater acting upon the steam at high pressures, the apparatus for attaining this result effecting a substantial economy of installation at such pressures.

25 Further objects of the invention will appear from the following description of illustrative embodiments of the invention.

The invention will be described with reference to the accompanying drawings, in which:

30 Fig. 1 is a diagrammatic view in the nature of a vertical section, showing a system illustrating the invention.

Fig. 2 is a view similar to Fig. 1, but showing another embodiment of the invention.

35 Fig. 3 is a detail view, mainly in vertical section, showing the valve mechanism which controls the desuperheating.

Fig. 4 is a detail view showing one of the orifice plates in an intermediate header.

40 Fig. 5 is a view in the nature of a vertical section taken on the line 5—5 of Fig. 2.

45 Fig. 6 is a detail view showing the valve mechanism which may be employed in the system shown in Fig. 1.

Fig. 7 is a detail section of the valve mechanism of Fig. 6.

50 Fig. 8 is a plan view of the steam distributor in the desuperheater chamber.

In Fig. 1 there are shown 4 groups of tubes which preferably extend across a gas pass in which the gases are flowing in the direction indicated by the arrow 10. The tubes of the groups 12 and 14 are elements of a primary superheater. They are connected to an inlet header 16 and are arranged so that steam may flow therethrough the upper chambers 18 of intermediate headers 20.

A secondary superheater in which the tubes of groups 22 and 24 are subjected to heating gases of high temperature, receives steam which is passed through the primary superheater. Their inlet ends are connected to the lower chambers 5 26 of the intermediate headers 20, orifice plates 28 being disposed between the upper and lower chambers of the intermediate header. The outlet ends of the tubes of the groups 22 and 24 are connected to an outlet header 30 from which 10 steam is conducted through a main 32 to a point of use.

The illustrative superheater is intended for use in a power generating installation in which power is developed by steam turbines using steam 15 at pressures of the order of 1200# per square inch. Such turbines show marked increases in efficiency as the superheat approaches a constant value, and a high efficiency of the entire installation is attained. The present superheater 20 apparatus also is advantageous when used with furnaces developing heating gases of high temperatures. Such temperatures are of an order which would cause frequent burning of the tubes of the high temperature section of the super- 25 heater in the event of excessive deposits caused by solids contained in the steam entering those tubes. The apparatus now being described maintains the desired superheat standard and reduces the percentage of solids which might 30 otherwise deposit in the tubes of the secondary superheater.

In the illustrative apparatus a variable part of the steam passing from the primary superheater is subjected to a contact desuperheater 35 before it enters the inlet chambers 26 of the secondary superheater. The contact desuperheater includes a desuperheating chamber preferably formed by a cylindrical pressure vessel 34, of relatively small diameter and arranged in upright position. The upper part of the desuperheater chamber, and by far the major portion of the chamber constitutes a steam and water separator 33. In the lower part of the chamber there is maintained a body of water of a concentration 40 preferably less than that of the steam which passes therethrough from the primary superheater.

The annular steam distributor 36 is positioned below the water level in the desuperheater chamber and is provided with a large number of small lateral openings 35 from which steam passes in jets 37 through the water in the desuperheater chamber. Externally of the desuperheater chamber the steam distributor is connected with 55

the outlets of the primary superheater by connections which include the conduit 38 and the cross header 40. Nipples 42 join this header with the chambers 18 and a T 44 is included in the connections.

A second cross header 46 is positioned in front of the chambers 26 of the intermediate headers 20 and is connected thereto by a number of nipples 48. As shown, both cross headers are directly connected by the T 44 and the flanged fittings 50 and 52. When steam is being desuperheated the cross header 46 receives steam through a line 54 which is directly connected to the top of the steam and water separator 33.

When the conditions of operation are such that superheat is maintained at the desired temperature without intermediate desuperheating, the controlled portion of steam passes directly from header 40 to header 46 by their interposed connection without passing through the desuperheater. In the event, however, that the temperature of the superheated steam in the line 32 attains too high a degree, it is desirable that some of the steam passing from the header 40 to the header 46 be desuperheated. This is attained by movement of the valve 58 to such an intermediate position as that shown in Fig. 1 of the drawings. This valve is preferably pivotally mounted in the T 44 so that it can close off that part of the T communicating with the line 38 and establish direct communication through the T and between the headers 40 and 46. In order that the amount of steam desuperheated may vary directly with the increase in temperature of the steam in the outlet main 32 the valve is thermostatically controlled. The apparatus for accomplishing this result includes a thermally responsive element 60 mounted in the steam line 32 and connected to a valve actuator 62. The valve actuator is connected by a link 64 to a crank arm 66 mounted upon the valve spindle extension 68. This extension is illustrated clearly in Fig. 6 as being operatively connected with a main valve spindle 70 which is rotatably mounted in the walls of the T 44. The valve 38 may be welded or otherwise rigidly secured to the main valve stem 70. The valve spindle extension 68 is rotatably mounted in a finned gland 72, the outer end of which cooperates with the member 74 to provide a stuffing box. This arrangement of elements causes the condensation of any steam which may leak through the T 44 around the main valve stem 70 into the journal provided by the member 72 and the resulting water acts as a lubricant for the valve stem extension 68.

It is desirable that a constant water level be maintained in the lower part of the desuperheater chamber and that this water level be at a position considerably above the steam distributor 36, or at such a level as that indicated at 76 in Fig. 1 of the drawings. When this water level is maintained by the admission of feed water a suitable feed water regulator 78 is provided. This is connected to a tube 80 extending into the desuperheater chamber, and the tube 80 is connected to the fluid heater 82 preferably consisting of coils positioned above the water level. The coils are for the purpose of preheating the water by surface heating of the coils by steam from the steam space. After passing through the heater the feed water discharges from a spray head 84 which causes the water to form a conical spray in falling.

The fluid heater 82 is by preference a part of a feed water line to a boiler. In any case the

water in the fluid heater 82 must be close to the saturation temperature of the steam in order to prevent water hammer in the fluid heater. This condition may be attained by passing the water through a preheater before it passes to the fluid heater 82. In starting the operation of the illustrative apparatus steam is caused to flow through the desuperheater chamber for an appreciable length of time before water is allowed to flow through the fluid heater 82.

Before the steam passes out of the desuperheater chamber it is caused to pass through a steam and water separator which has an effective area much greater than the cross sectional area of the desuperheater chamber. This separator is shown as including a number of ring sections which are spaced vertically of the chamber, and are of smaller and smaller diameter as the top of the desuperheater chamber is approached. The lower ring section 90 is preferably secured to the wall of the chamber in the position shown and has an annular channel 92 communicating with a drain tube 94 extending downwardly in the desuperheater chamber and having its outlet at one side of the feed water heater 82.

The ring section 96 next above the section 90 presents an upwardly opening channel 98 and a downwardly opening channel 100, the diameter of the latter channel being substantially the same as that of the channel 92. Extending from the ring section 90 to the ring section 96 and disposed in the channels 92 and 100 is an annular band 102 of granular or fibrous material which may be held in place by any suitable means such as perforate plates. The channel 98 has a drain pipe 104 which is at one side of the feed water heater. As shown, the remaining parts of the separator are constructed and arranged similarly to those above described, and the entire construction is such that all of the desuperheated steam must pass through the granular or fibrous material before it emerges from the desuperheater and passes through the conduit 54 to the header 46.

The desuperheater is provided with a water gauge construction 106 and there is a drain 108 for the desuperheater chamber, to be used to control the concentration of the water. The flow through the drain 108 can be governed by the valve 110 so that the concentration of the water in the desuperheater can be less than the concentration of steam that enters the desuperheater from the primary superheater.

In the embodiment of the invention shown in Figs. 2 and 5, the steam leaving the primary superheater may be led directly to the desuperheater chamber 112 through a plurality of conduits 114. Internal upright tubes 116 constitute substantial extensions of the conduits 114 and are arranged within the desuperheater chamber as clearly indicated in Figs. 2, 3, and 5. At the lower ends of these tubes there are disposed steam distributing manifolds 118 positioned beneath the water level 120 which is maintained by a feed water regulator 122 disposed in a line 124 leading to the feed water heater 126, the arrangement and functioning of these elements being somewhat similar to those in the Fig. 1 embodiment.

Desuperheated steam is led directly from the desuperheater chamber 112 to the inlet chambers 26 of the secondary superheater by conduits 130 which are connected to the tubes 116 within the desuperheater chamber as clearly shown in Fig. 3 of the drawings. This figure discloses flanged

tubular drum connections 162 preferably expanded in openings in the wall of the chamber 112 and welded to that wall as indicated at 134. Within the flanged portion 136 there is positioned 5 a perforated tube 138. This tube is preferably held rigid with the connections 134 by a circumferential weld 140.

Each tube 138 has a perforate section 142 which joins the tube 116. At this point of juncture 10 there is arranged a valve 144 which may rotate from the position indicated in full lines to that indicated in dotted lines. In the full line position shown, no steam is being desuperheated, all 15 of the steam coming from the primary superheater passing through the connections shown in Fig. 3 directly to the secondary superheater. When the valve is in its dotted line position all steam passing through the conduits 114 is de- 20 superheated before it passes to the secondary superheater. Different amounts of steam will be desuperheated depending upon the intermediate position to which the valve is moved. In order that the amounts of steam desuperheated may vary directly as the temperature changes in the 25 line 32 the valve 144 is connected to a valve actuator 146 which is governed by a thermally responsive element 147 disposed in the line 32. The connections between the valve 144 and the actuator 146 include a rock shaft 148 connected 30 to the actuator by a link 150. This connection is externally of the desuperheater chamber, the rock shaft passing into the chamber through a stuffing box 152 and being rotatably mounted in supports 154 which are fixed to the wall of the 35 chamber. Each valve has a crank arm 156 rigid therewith, and the outer end of each crank arm is connected to a rock arm 158 rigidly mounted on the rock shaft. This connection is through a link 160.

40 As indicated in Fig. 3 mounting of the tubes 116 in the drum is carried out in the same manner in which the tubes 138 are mounted. Connections for accomplishing this include the tubular drum connectors 162, and the circumferential welds 164 and 166.

The desuperheater chamber 112 is provided with a gauge glass 170 and a drain pipe 172 by the control of which the concentration of the water in the desuperheater chamber may be maintained 50 at a figure preferably less than that of the concentration of the steam to be desuperheated.

Fig. 2 shows the superheater casing 174, which 55 confines the heating gases so that they will contact with the superheater elements. It will be understood that the arrangement of superheater tubes of the Fig. 1 modification will, in practice, be positioned within a gas pass which is formed by such a casing as that illustrated in Fig. 2.

It will also be understood that, in practice, the 60 various conduits must be arranged somewhat differently than they are shown in the drawings. For example, the conduits 38 and 54 as shown in Fig. 1 of the drawings must be offset or provided with large radius bends where they cross 65 each other.

Relative to the thermally responsive devices shown in the drawings it will be understood that the elements 60 and 147 are connected to the valve actuator mechanisms 62 and 146 by tubes 70 176 and 180 which contain expandable fluid.

The steam distributor 36 is shown in detail in Fig. 8 of the drawings. It preferably consists of two annular parts 182 and 194, the latter being mounted within the former and held rigid there- 75 with by connecting members 186. These annular

parts may have a cross section such as that indicated in Fig. 1 of the drawings and they are joined by a connector 188, preferably located opposite the steam inlet for the distributor.

Referring again to the steam and water separator 5 in the upper part of the pressure vessel 34 it will be understood that above the annular band 102 there are mounted similar bands 190, 192, etc., until a top-most band 194 of relatively small diameter is reached. A cap 196 prevents the steam from freely flowing from the separator without first passing through the granular or fibrous material of the bands. At the top of the pressure vessel 34 there is provided a manhole 200 through which there may be access to the parts of the steam and water separator. This manhole is normally closed by the members 202, 204 and 206.

The valve construction shown in detail in Fig. 6 of the drawings is intended to indicate 20 that the finned gland 72 is rigidly held against the annular boss 208 formed on the side of the T 44. It may be detachably secured thereto by bolts.

At the other end of the finned gland 72 there is 25 a stuffing box construction which includes a flange sleeve 210. The latter may be secured to the flange portion 212 of the finned gland by means of bolts so as to compress packing material 214. The valve spindle extension 68 has on 30 its inner end an enlarged portion 216 which forms a shoulder bearing against the left-hand end of the finned gland and the main valve spindle 70 is shown as formed with a transverse recess 218 in which there is located a transverse rib 220 pref- 35 erably formed integrally with the enlarged portion 216. It is to be understood that the valve construction indicated in Fig. 6 of the drawings may be employed in connection with the various valves in the tubular extension 116 of the Fig. 5 40 modification. This valve construction presents the advantage that the main valve spindle 70 may be made of a material different from that of the extension 68. The extension 68 is not subjected to the same conditions of temperature and fluid 45 flow which affect the operation of the main valve spindle 70.

It will be understood that the orifice plates 28 may be removed and that other plates having orifices of different sizes substituted therefor.

The illustrative apparatus which involves an 50 upright cylindrical desuperheater chamber has the advantage of lower cost of installation, together with the advantage of permitting the installation of a steam and water separator which 55 has a separating area much greater than the cross section of the desuperheater, or separator chamber.

In the operation of the apparatus shown in Fig. 1 it is to be appreciated that there will be a 60 change in the quality of the steam entering the desuperheater chamber. A considerable portion of whatever solids may be carried by the steam will be removed and the life of the tubes of the high temperature section of the superheater will 65 be correspondingly increased.

While the invention has been described with reference to the particular embodiments shown in the accompanying drawings, it is to be understood that the invention is not limited thereto, but that 70 it is of a scope commensurate with the scope of the subjoined claims.

What is claimed is:

1. In steam conditioning apparatus, a primary superheater section, a second superheater section 75

- subjected to a heating medium at higher temperature, connections providing for a continuous flow of part of the steam leaving the primary section directly to the second section without intermediate desuperheating, a desuperheater including a water chamber, a regulator for maintaining a predetermined supply of water in the chamber, a by-pass means causing steam from the primary section to pass through the water in said chamber and then to the second section in amounts directly proportional to variations of the exit temperature of the steam from the second section, and means including elements of the by-pass means associated with the desuperheater to cause a part of the by-passed steam to pass directly to the second section without contact with the water in the desuperheater chamber and to vary the latter part inversely as the exit temperature of the steam from the secondary section.
- 20 2. The method of superheating steam and regulating the temperature thereof which consists in supplying steam to a high temperature superheater and raising its temperature therein, leading the superheated steam from the superheater to the point of use at substantially the exit temperature of the superheater, regulating the exit temperature of the superheated steam from the superheater by supplying it with superheated steam at a temperature which varies inversely as the temperature of steam leaving said superheater, and conditioning the inlet steam supplied to the high temperature superheater by causing the inlet steam to pass through water and then in counter-flow relation through a spray in amounts which vary directly with the temperature of the steam leaving the superheater.
3. In apparatus for superheating steam and controlling the final temperature thereof, a first superheating section of low temperature, a second superheating section of high temperature subjected to the same furnace gases as the first section, connections imposing a fixed resistance to the flow of steam from the first section to the second but always permitting a certain steam flow, a desuperheater chamber, tubular means establishing communication between the outlet of the first section and the lower part of the chamber at a position below its water level, steam distributors at the outlet ends of said means, feed regulating devices for maintaining such a predetermined water level in the chamber that there is a large separation space above that level, a steam and water separator in said space, means connecting said space and the inlet of the high temperature section, a by-pass through which communication is established between said tubular means and the inlet of the second section above the water level, means varying the steam flow through the by-pass inversely to superheat changes at the outlet of the second section and varying the steam flow through the distributors directly with said superheat changes.
4. In a device for superheating steam and regulating the temperature thereof, a fuel-fired superheater in which the temperature of the steam is raised, means for conducting the superheated steam from said superheater to a point of use at substantially the exit temperature from the superheater, and means including a second superheater and a controlled direct action desuperheater for regulating the exit temperature of the superheated steam from the first mentioned superheater by adding varying amounts of heat to the steam entering the first mentioned superheater, said desuperheater including means

providing a water spray through which the steam must pass after passing through a body of water in the desuperheater.

5. In a device for supplying superheated steam, a first and a second stage of superheating involving the preheating of steam before it reaches the second stage, means for feeding steam in a successive manner from a source of supply through the two stages of superheating, means for heating the steam in second stage of superheating by 10 furnace gases at a temperature higher than the heating gases of the first stage, a direct action desuperheater including a spray head above a body of water and steam supply means below the surface of the body of water, said desuperheater 15 being located between the stages and causing the steam to be spray washed after it passes through a body of water and before it reaches the second stage, and means for varying the amounts of pre-heating of the steam before it is delivered to the 20 second stage.

6. In superheat regulating apparatus, a primary superheating section of low temperature in which steam is heated by furnace gases, an upright cylindrical pressure vessel acting as a desuperheater chamber and having a large ratio of height to its diameter, a steam heated fluid heater in the pressure vessel, means at the outlet of said fluid heater for causing the fluid discharged therefrom to form a spray, means associated with the heater to control the flow of fluid therethrough and maintain a water level in the lower part of the chamber, an annular steam distributor mounted in the chamber below said water level, means for connecting the outlet of said low temperature superheater section to the steam distributor so that steam will pass up through the water in the bottom of the pressure vessel, a steam and water separator in the upper part of said pressure vessel for separating water from the steam which proceeds from the distributor and past the spray, a high temperature superheater section constantly receiving a part of the steam directly from said low temperature section, means connecting the steam and water separator to the inlet of said high temperature section, a bypass connecting the outlet of the low temperature section and the inlet of the high temperature section, and means associated with the bypass to vary the amount of steam passing through the bypass inversely as the temperature of steam varies at the outlet of the high temperature section.

7. In the superheating of steam for power purposes, generating steam, imparting a primary degree of superheat to the generated steam, subjecting a part of the resulting superheated steam to a steam washing action wherein the superheated steam is contacted with water to effect desuperheating and a reduction in the entrained solids, subsequently separating water from the steam leaving said water contact by an action in the nature of a mechanical filtration, returning the washed and purified steam to a high temperature superheating zone wherein the washed steam joins steam passing directly from the zone of primary superheat, and maintaining an inverse ratio between temperature of the steam at the outlet of the high temperature superheating zone and the part of the generated steam which is not subjected to the steam washing action.

8. In a superheater including a high temperature section and a low temperature section, a direct contact desuperheater including an upright cylindrical pressure vessel operatively interposed

- relative to the sections, means for maintaining a predetermined water level in the desuperheater, a separator in the pressure vessel above said level and having a steam and water separating area 5 greater than the cross section of the vessel, means for causing a proportion of the steam leaving the low temperature section to pass through the water in the desuperheater, and means for varying said proportion directly as the temperature of 10 the steam leaving the high temperature section, said last named means also varying the temperature of the steam at the inlet of the high temperature section inversely as the exit temperature of the steam from that section.
- 15 9. In steam conditioning apparatus, a primary superheater section, a secondary superheater section subjected to heating gases of higher temperature, connections providing for a continuous flow of part of the steam leaving the primary 20 section directly to the secondary section without intermediate desuperheating, a desuperheater including an upright cylindrical water chamber, a regulator for maintaining a predetermined water level in the chamber, a steam and water separator 25 above said water level, means causing steam from the primary section to pass through the water in said chamber and then to the secondary section in amounts directly proportional to the exit temperature of the steam from the secondary section, 30 and means associated with the desuperheater to cause a part of the steam from the primary section to pass directly to the secondary section without contact with the water in the desuperheater chamber and to vary that part inversely 35 as the exit temperature of the steam from the secondary section.
10. The method of superheating steam and regulating the temperature thereof which consists in supplying steam to a high temperature 40 superheater and raising its temperature therein, leading the superheated steam from the superheater to the point of use at substantially the exit temperature of the superheater, regulating the exit temperature of the superheated steam 45 from the superheater by supplying it with superheated steam at a temperature which varies inversely as the temperature of steam leaving said superheater, and conditioning the inlet steam supplied to the high temperature superheater by washing and subsequent filtering in amounts 50 which vary directly as the temperature of the steam leaving the superheater.
11. In the production of superheated steam for power purposes, generating steam, imparting a primary degree of superheat to the generated steam, subjecting a part of the resulting superheated steam to a steam washing action wherein the superheated steam is contacted with water to effect desuperheating and a reduction in the 55 entrained solids, subsequently separating water and any entrained solids from the steam leaving said water contact by an action in the nature of a mechanical filtration, returning the washed and purified steam to a high temperature superheating zone wherein the washed steam joins steam passing directly from the zone of primary superheat, utilizing furnace gases as the heating medium in the high temperature zone and maintaining an inverse ratio between temperature of the 60 steam at the outlet of the high temperature superheating zone and the proportion of the generated steam which is not subjected to the steam washing action.
12. In steam treating apparatus, a pressure vessel forming a steam chamber, means for main-
- taining a water level in said chamber, means for causing steam to be discharged in the chamber below said level, a fluid heater above the level, discharge means whereby said heater discharges a spray of water across the chamber and downwardly toward said level, a filter type steam and water separator positioned above said discharge means and having a separating area greater than the cross section of the chamber, and steam discharge means at the upper part of the chamber. 10
13. In a superheater including a high temperature section and a low temperature section, a direct contact desuperheater operatively interposed relative to the sections, means for maintaining a predetermined water level in the desuperheater, 15 means for causing a part only of the steam leaving the low temperature section to pass through the water in the desuperheater before it reaches the high temperature section, means providing a water spray through which the steam must pass 20 after leaving said water, a steam and water separator above said spray means, and means for varying said part in direct proportion to temperature changes in the steam leaving the high temperature section, said last named means also 25 varying the temperature of the steam at the inlet of the high temperature section inversely relative to temperature changes in the steam from that section.
14. In superheat regulating apparatus, a primary superheating section of low temperature in which steam is heated by furnace gases, a pressure vessel presenting a desuperheater chamber and a large steam and water separator space, a steam heated fluid heater in the pressure vessel, 30 means at the outlet of said fluid heater for causing the fluid to be discharged therefrom downwardly in the form of a spray, means associated with the heater to control the flow of fluid therethrough and maintain a desired water level in 35 the lower part of the chamber, a plurality of steam distributors mounted in the chamber below said water level, means for connecting the outlet of said low temperature superheater section to the steam distributors so that steam will 40 pass up through the water in the bottom of the pressure vessel, a steam and water separator in the upper part of said pressure vessel for separating water from the steam which proceeds from the distributor and then through the spray, a high 45 temperature superheater section constantly receiving a part of the steam from said low temperature section before it passes to the distributor, means connecting the steam and water separator to the inlet of said high temperature section, a bypass connecting the outlet of the low 50 temperature section and the inlet of the high temperature section, and means associated with the bypass to vary the amount of steam passing through the bypass inversely as the temperature 55 of steam varies at the outlet of the high temperature section.
15. In the superheating of steam for power purposes, generating steam, imparting a primary degree of superheat to the generated steam, subjecting a part of the resulting superheated steam to a steam washing action wherein the superheated steam is passed through a body of water of a concentration less than that of the superheated steam and contacted with a water spray 60 to effect desuperheating and a reduction in the entrained solids, subsequently separating water from the steam leaving said water contact, returning the washed and purified steam to a high 65 temperature superheating zone wherein the
- 70
- 75

washed steam joins steam passing directly from the zone of primary superheat, and maintaining an inverse ratio between temperature of the steam at the outlet of the high temperature superheating zone and the part of the generated steam which is not subjected to the steam washing action.

16. In a superheater including a high temperature section and a low temperature section, a direct contact desuperheater including a pressure vessel operatively interposed intermediate said sections, means for maintaining a predetermined water level in the desuperheater, a steam and water separator in the pressure vessel above said level, means for causing a part only of the steam leaving the low temperature section to pass through the water in the desuperheater, and means for varying said part in a ratio directly related to temperature changes in the steam leaving the high temperature section, said last named means also varying the temperature of the steam at the inlet of the high temperature section inversely to changes in the exit temperature of the steam from that section.

17. In steam conditioning apparatus, a primary superheater section, a secondary superheater section subjected to heating gases of higher temperature, connections providing for a continuous flow of part of the steam leaving the primary section directly to the secondary section without intermediate desuperheating, a desuperheater including a water chamber, a regulator for maintaining a predetermined water level in the chamber, a steam and water separator above said water level, means causing steam from the primary section to pass through the water in said chamber and then to the secondary section in amounts directly proportional to the exit temperature of the steam from the secondary section, and means associated with the desuperheater to cause a part of the steam from the primary section to pass directly to the secondary section without contact with the water in the desuperheater chamber and to vary that part inversely as the exit temperature of the steam from the secondary section.

18. The method of superheating steam and regulating the temperature thereof which consists in supplying steam to a high temperature superheater and raising its temperature therein, leading the superheated steam from the superheater to a point of use at substantially the exit temperature of the superheater, regulating the exit temperature of the superheated steam from the superheater by supplying it with superheated steam at a temperature which varies inversely as the temperature of steam leaving said superheater, and conditioning a part of the inlet steam supplied to the high temperature superheater by washing in amounts which vary directly as the temperature of the steam leaving the superheater.

19. In the production of superheated steam for power purposes, generating steam, imparting a primary degree of superheat to the generated steam, subjecting a part of the resulting superheated steam to a steam washing action wherein the superheated steam is contacted with water to effect desuperheating and a reduction in the entrained solids, subsequently separating water and any entrained solids from the steam leaving said water contact returning the washed and purified steam to a high temperature superheating zone wherein the washed steam joins steam passing directly from the zone of primary superheat, utilizing furnace gases as the heating medium in the high temperature zone and maintaining an inverse ratio between temperature of the steam at the outlet of the high temperature superheating zone and the proportion of the generated steam which is not subjected to the steam washing action.

20. In steam treating apparatus, a pressure vessel forming a steam chamber, means for maintaining a water level in said chamber, means for causing steam to be discharged into the chamber below said level, a fluid heater above the level, said heater including tubular elements heated by the steam discharged into the chamber by said second mentioned means, discharged means whereby said heater discharges a spray of water across the chamber and downwardly toward said level, a steam and water separator positioned above said discharge means, and steam discharge means at the upper part of the chamber.

21. A steam heating and temperature regulation system including, in combination: a pair of steam heater sections arranged for serial flow of gases across the tubes thereof; a connection between said sections providing for serial flow of steam therethrough; the arrangement of the sections being such that the second stage heater section is in advance of the first stage with respect to the direction of gas flow; a desuperheater; connections extended between said heater sections and said desuperheater and providing for flow of steam serially through the first stage heater section, the desuperheater and the second stage heater section; and regulator valve means associated with said connections for controlling the amount of steam passing directly from the first stage heater section to the second stage and from the first stage heater section through the desuperheater to the second stage; the said connections being arranged to provide for the mixing or intermingling of the steam passing through the second stage heater section through said desuperheater and directly from the first stage heater section prior to the time of entrance of the steam into the elements of the second stage heater section.
